J. H. WHEELOCK.

SOUND PRODUCER.

APPLICATION FILED JULY 18, 1917.

1,312,373.

Patented Aug. 5, 1919.

UNITED STATES PATENT OFFICE.

JOHN H. WHEELOCK, OF WORCESTER, MASSACHUSETTS, ASSIGNOR TO KLAXON COMPANY, OF NEWARK, NEW JERSEY, A CORPORATION OF DELAWARE.

SOUND-PRODUCER.

1,312,373.

Specification of Letters Patent. Patented Aug. 5, 1919.

Application filed July 18, 1917. Serial No. 181,194.

To all whom it may concern:

Be it known that I, JOHN H. WHEELOCK, a citizen of the United States, residing at Worcester, in the county of Worcester and 5 State of Massachusetts, have invented a new and useful Sound-Producer, of which the following is a specification.

This invention relates to electro-magnetic horns particularly to those in which two 10 elastic vibrators are reciprocated through a single rod or plunger. The latter is preferably actuated by an electro-magnet energized by suitably varying currents, preferably by alternating currents, though fluctuating or interrupted currents may be employed.

One object of the invention is to provide exceedingly simple mechanism having no parts likely to get out of order or out of 20 place under conditions of practical use.

Another object is to provide a two-diaphragm horn having a single intermediate actuator, these three moving elements being coördinated and arranged so as to vibrate 25 in the greatest possible mechanical harmony and efficiency and with the least possible mechanical or acoustical interference.

Reference is to be had to the accompanying drawings, in which—

30 Figure 1 is an elevation of a double horn constructed in accordance with this invention with parts in section to show the operating mechanism inside, and

Fig. 2 is a transverse sectional view of the 35 line 2—2 of Fig. 1.

In the form of the invention shown two horns 10 of any usual construction are provided and a cylindrical casing 11 which may be formed of cast or pressed metal. This 40 casing is provided with a substantially flat end 12 which has a flat-topped circumferential ridge 13 to provide a space for a sounding diaphragm 14.

Extending across the casing is shown a 45 diametrical integral solid cross piece 16 designed to support the operative mechanism inside. At the other end the casing 11 is provided with a second flat circumferential ridge 13 on which is a second diaphragm 19. 50 These two diaphragms 14 and 19 are thus arranged in parallel relation to each other and located substantially at the ends of the casing, each of them communicating directly with a horn. The diaphragms are pref-

erably substantially identical in size, thickness, material and peripheral clamping. Adjusting screws 15 are employed to control the tension and tone of the diaphragms.

In this form there is an electro-magnet comprising two coils 20 each provided with 60 a fixed steel or soft iron core 21 which is headed over on the inside preferably, so that the coils are firmly secured to the cross piece 16. The usual wires are shown for connection of the electro-magnet with a 65 source of suitably varying electric currents, preferably the alternating current source diagrammatically indicated at G, Fig. 2.

In addition to these features, the cross piece 16 is provided with a guide perforation 24. Extending through this perforation is a plunger 25, one end of which is fixedly connected with a soft iron armature 26. The two ends of the plunger are a sufficient distance apart to abut at all times 75 against the two diaphragms so as always to engage both of them at the same time and move back and forth with them.

The operation of the device is very simple. When the current is operating to magnetize the cores, the armature will be attracted in such a direction as to cause the plunger to force out one diaphragm as for example the diaphragm 19. The immediate effect of this is to distort the diaphragm, 80 spring it away from the core, and its reaction throws the plunger back and distorts the diaphragm 14 while the cores are demagnetized during the alternation of the current. Then the diaphragm 14 reacts 90 and starts the plunger in the opposite direction, the re-magnetization of the cores assisting in its outward thrust on the diaphragm 19. In this way both diaphragms are operated to produce their maximum sound. The 95 effect secured from the second diaphragm is entirely additional to what is usually obtained and is added with the use of practically no additional current.

By arranging the plunger so that it is 100 initially in firm contact with both diaphragms, the parts may be forced to vibrate substantially in synchronism. If necessary the screws 15 may be adjusted to slightly change the normal elastic tensions of the 105 diaphragms to perfect the harmonizing of their elastic or resilient reactions until the synchronism of action of all three elements

becomes practically perfect. This will be evidenced by the note becoming clearer and more resonant.

When such a horn is used on a commercial alternating circuit of say 60 cycles per second, the current flowing in one direction for a half cycle and then in the other direction for a half cycle, operates to energize the magnet at the rate of 120 magnetizations per second with intermediate stages of little or no magnetization when the current is decreasing to zero and reversing its direction. The armature on the plunger will therefore be attracted by the magnets 120 times per second thereby causing 120 one-direction forcing movements of the plunger, the 120 intervals of reversing magnetism permitting free elastic return movements or swings back to and beyond the normal position of rest. Hence, in order to obtain the best results, the vibratory systems including the two diaphragms and the intermediate plunger, should be selected and adjusted so as to have a natural time period of approximately 120 complete to and fro swings per second. When this is done, the succession of one-direction pulls operates cumulatively to increase the extent or amplitude of the swings without changing their number per second and without any tendency of the diaphragms to get out of step with each other or with the plunger.

When the diaphragms are in full swing, the plunger operates as a load, first on one diaphragm and then on the other, during the inward, resilient part of the swing, and it will be noticed that when the diaphragms are normally bowed inward by the peripheral clamps or by the screws 15, 15, as indicated in the drawing, the resilient power of the diaphragm will be greatest at the instant when it is most needed. Moreover, at that same instant, the other diaphragm, the one which is free from the load, will be in its position of least resilience. In other words, when thus arranged, the first part of the inward movement of the diaphragm when it must assist in propelling the plunger, is more powerful than the first part of the outward movement when it is not carrying the plunger as a load.

The initial outward bowing of both diaphragms by the plunger acting as a thrust member between them may be and preferably is great enough so that the spring pressure of both diaphragms on opposite ends of the plunger is never wholly relaxed, not even at the innermost point of the most violent swings.

While these conditions may be perfected to a point where neither diaphragm ever loses physical contact with its end of the plunger, it is necessary only that this action be perfected sufficiently so that the parts will always be moving substantially in the

same direction at the same time, that is, substantially without mechanical interference. This condition may be easily determined by listening to the sound produced. Loud, clear, non-interfering notes proceeding from both diaphragms is a sure indication that great amplitude of vibration has been built up by substantially non-interfering co-operation of all of the forces acting in and upon all parts of the vibratory system. 75

In assembling the parts the holding bolts 27 are tightened up until the diaphragms are sprung slightly inwardly between the edge and center. They usually bulge out at the center because of the contact with the plunger. The adjusting screws 15 can be turned to regulate the sound of both diaphragms, usually to tone it down. All the sound is obtained by the vibration of the diaphragms alone and it is not interfered with by any tapping of the plunger upon them. This I find to be a material improvement over the art in which it was supposed that the sharp impact of a striker on the diaphragm was needed to cause a loud sound. 90

It will be observed that the operative parts are reduced to an exceedingly simple arrangement. The plunger has no springs connected to it, no pivoted parts are used, and there are no jointed connections of any kind. Furthermore, the plunger always acts axially and cannot get out of alignment or into any inoperative position.

Although I have illustrated and described only one form of the invention, I am aware 100 of the fact that many modifications can be made therein by any person skilled in the art without departing from the scope of the invention as expressed in the claims. Therefore I do not wish to be limited to all the 105 details of construction herein shown and described, but what I do claim is—

1. A sound producer comprising a pair of parallel diaphragms, a plunger between them in contact with both, means for holding said diaphragms in such position that they bulge outwardly at the center and at the edge and are concave on their outer surfaces at points between. 110

2. A sound producer comprising a pair of parallel diaphragms, a plunger between them in contact with both, means for moving said plunger in one direction toward one diaphragm, said diaphragm constituting the sole means for moving the plunger 120 and the other diaphragm in the other direction.

3. A sound producer comprising a pair of parallel diaphragms, a plunger between them in contact with both but unattached to either, means for moving said plunger in one direction toward one diaphragm, the other diaphragm being arranged to move simultaneously in the same direction. 125

4. In a sound producer, the combination 130

- of a resilient sound producing element, a floating vibrator movable toward and from the same, means for drawing the vibrator toward said element far enough to flex it 5 and then releasing the vibrator, said element constituting the sole means for forcing the vibrator in the opposite direction by its recoil, and a second resilient sound producing element spaced from the first one and 10 located in position to be vibrated by said vibrator when moved under the influence of the first named element.
5. In a horn, two parallel similar diaphragms and a plunger between and perpen-
- dicular to both of them, said diaphragms 15 being initially sprung outwardly at the center by said plunger acting as a thrust member.
6. In a horn, two parallel similar dia- 20 phragms and a plunger between and perpendicular to both of them, said diaphragms being peripherally sprung inward toward each other and at the center, initially sprung in the opposite direction by said plunger 25 acting as a thrust member.

In testimony whereof I have hereunto affixed my signature.

JOHN H. WHEELOCK.
